UNITED STATES PATENT OFFICE.

LESLIE OLIAN, OF ST. LOUIS, MISSOURI.

LANTERN-HOLDER.

979,550.

Specification of Letters Patent. Patented Dec. 27, 1910.

Application filed August 9, 1909. Serial No. 512,006.

To all whom it may concern:

Be it known that I, LESLIE OLIAN, a citizen of the United States, residing at the city of St. Louis, State of Missouri, have invented 5 a new and useful Improvement in Lantern-Holders, of which the following is a specification, reference being had to the accompanying drawing, forming a part hereof, in which—

10 Figure 1 is a side elevational view of my new lantern-holder, showing the same in position on a dash-board and a lantern supported thereby; Fig. 2 is a perspective view of my new lantern-holder; and Fig. 3 is a 15 cross-sectional view on the line 3—3, Fig. 1.

This invention relates to a new and useful improvement in lantern-holders, the object being to provide a neat, simple, and attractive device of the kind described, which 20 can be manufactured at comparatively slight cost.

With this object in view, my invention consists in the novel construction of my lantern-holder, all as will hereinafter be described and afterward pointed out in the 25 claims.

As shown in the drawings, my lantern-holder is preferably made or formed of one piece of comparatively strong, spring wire, 30 which is bent or doubled upon itself, as at 1, thereby providing the two strands 2 and 3. The strands 2 and 3 are first bent or spread apart for a short distance, providing the loop 4, which is adapted to bear or impinge 35 against the back of the dash-board or other support 5 when the holder is in operative position. The said strands 2 and 3 are then brought together and intertwined, as shown in Figs. 1 and 2, throughout their length, 40 except at their ends, providing the body portion 6 of the holder, which body portion is bent or doubled, as at 7, see particularly Fig. 1, forming a substantially U-shaped spring clip which is adapted to be slipped 45 over and yieldingly fit upon said dash-board or other support 5. As shown in Figs. 1 and 2, the end 8 of strand 2 is preferably slightly curved or bent outwardly, while the end 9 of strand 3 is doubled or rounded upon 50 itself, thereby providing the closed eye 10, through which a screw or bolt 11 is adapted to pass to hold a lantern 12 firmly in position thereon.

The wire of my holder is sufficiently resilient or springy, so that, when the holder 55 is in position on a dash-board or other support, it will not readily or easily become dislodged from its proper position by any shocks or jars imparted to said dash-board or other support, the loop 4 providing a 60 firm broad bearing for the holder against the rear of said dash-board or other support 5, while the strands 2 and 3, preferably at the end of said body portion 6, bear or impinge firmly against the front of said 65 dash-board or other support.

My holder, as will be seen, is sufficiently strong for all uses to which it is applicable; it is simple and inexpensive; and while, as stated, it will not readily become dislodged 70 from proper position on a support by shocks or jars, yet it may be easily removed from said support with the lantern attached and afterward again placed in proper position by the user whenever desired. 75

Having thus described my invention, what I claim and desire to secure by Letters Patent is:

1. A lantern-holder comprising a single piece of wire doubled into two strands, said 80 strands being intertwined throughout the greater part of their length and bent substantially U-shaped, thereby providing an intertwined body portion adapted to yieldingly fit on a support, and one of said 85 strands being doubled upon itself at its end to provide a lantern-supporting eye; substantially as described.

2. A lantern-holder comprising a single piece of wire doubled into two strands, said 90 strands being first spread apart to provide a bearing-loop 4 and then intertwined to provide a body-portion 6, the said intertwined body-portion being bent substantially U-shaped and adapted to yieldingly 95 fit on a support, and one of said strands being doubled upon itself at its end to provide a lantern-supporting eye; substantially as described.

3. A lantern-holder comprising a single 100 piece of spring wire doubled into two strands, said strands being first spread apart to provide a bearing-loop 4 and then brought together and intertwined throughout their length, except at their ends, providing an 105 intertwined body-portion 6, said body-portion

tion being bent substantially U-shaped and adapted to yieldingly fit on a support, one of said strands being doubled upon itself at its end to provide a lantern-supporting eye, and the end of the other of said strands being bent outwardly and projecting below said eye; substantially as described.

In testimony whereof, I have signed my name to this specification in the presence of two subscribing witnesses.

LESLIE OLIAN.
